LUMINOUS TUBE SIGN

Arthur Clifton Deans, Los Angeles, Calif.

Application August 31, 1936, Serial No. 98,685

9 Claims.

(Cl. 40—130)

This invention relates to a luminous tube electric sign and the main objects thereof are to improve the appearance and readability, increase the light intensity of the tubes and increase the efficiency of the sign with regards to the energy consumed.

With the prior art signs a large percentage of the light is radiated onto the background. In order to conserve as much as possible of the light the letter strokes behind the tubes are often of light color. It is well known that readability decreases with the increase of the letter stroke.

It is an object of this invention to reflect the light which would ordinarily be sent onto the background by means of a mirror surface on the back side of the tube itself. Thus, the light source presented to the eye is no wider than the tube itself, thereby increasing the readability. One should also bear in mind that a mirror surface on glass has a high luminous efficiency which does not change with time, whereas a paint surface on metal has a low luminous efficiency and falls off rapidly with the aging of the paint and the accumulation of dirt.

The advantages of this device are many. The entire angle of rays which are not sent directly forward from the glowing gas is thus conserved. With the prior art, even with the widest letter stroke permissible, only a fraction of the light sent backward is caught. Often this fraction is no more than one third, and rarely is it over one half of the backward light.

Another common practice of the prior art involves the construction of channels around the tubes to conserve the light. With signs made according to this invention the practice of providing channels or troughs for the tubes may be dispensed with entirely. The sign characters may be painted on the body of the sign proper or they may be raised slightly as shown in the drawings. The invention is equally adaptable to skeleton letter signs.

With the present invention tubes may be formed up in the representation of words and supported in the air without backgrounds. Such, for instance, might be done to advantage by providing a tube in the form of an extra word or ornamentation projecting above, below or to the side of a regular type of sign. The reflector on the tube obscures the light in the reverse direction and the efficiency in the proper direction is every bit as high as though the tube were made to appear on a background. Various other adaptations of the invention will be apparent to those

skilled in the art, all within the purview of the claims.

Another object of the invention is to provide means to prevent electrical breakdown between critical points of a configurated tube provided with a metallic reflective coating. Such critical points are found where points spaced along the length of the tube approach each other at cross overs, return bends, parallel bends, etc. It has generally been believed that the breakdown tendency was more or less a direct function of the stress imposed on the glass by the proportionate voltage drop between such points as regards the total voltage drop between the terminals of the tube. I have found that the breakdown tendency develops in a very different manner than this theory would indicate and apparently follows some law as yet unexplained. This tendency is materially in excess of what was expected with tubes with a continuous coating along convoluted portions. However, in accordance with my invention, tubes of the character described may be manufactured and installed with the same facility as ordinary tubes and will operate entirely satisfactorily under all conditions.

Other objects of the invention will become apparent as the description proceeds. Since the invention may be variously modified within the broad principles herein disclosed it is my intention that it be not limited to the particular embodiments herein disclosed but be interpreted to cover all modifications and embodiments within the broadest language of the claims.

The preferred form of the invention is shown in Figures 1 and 2 in which a sign is shown with raised type letters and with a tube provided with a reflective coating positioned a short distance in front of the letters.

Figure 3 is a cross section, very much enlarged, of a tube provided with a reflective coating and a protective coating over it.

Figure 4 is an enlarged view in perspective of the upper part of the letter "t" to show the manner of providing the coating. It is taken at the same angle of view as that of Figure 2.

Figure 5 is an enlarged view of the letter "e" taken at the same angle of view as that of Figure 2.

Figures 6, 7, 8, 9 and 10 are sectional views taken as indicated by the sections lines 6—6, 7—7, 8—8, 9—9 and 10—10, respectively, in Figure 1. In these views the coatings are greatly exaggerated in thickness for purposes of illustration.

The same numeral is used throughout all of the views to indicate the same part or element.

Numeral 1 indicates a sign body on which is constructed the raised character form indicated by 3, 3, etc. The character outline is in representation of the word "Rite" in script. The luminous tube, indicated by 2, follows the form of the character and is positioned a short distance from the character faces by means of the insulating posts 8, 8, etc. The ends of the tube are formed as electrode terminals, 6 and 7, which extend backward into the terminal housings, 4 and 5. Within the sign, but not shown on the drawings, are the usual transformer and high tension connections.

In forming certain letters with luminous tubes it is always necessary to bend the tube to return over its own course at certain places. These return bends are usually made with one part of the tube behind the other as shown in the drawings. However, it is also permissible to form them with the tube all lying in the same plane, that is to say, with the return bends beside the tube portions which properly represents the corresponding character element. The principles of the instant invention apply equally well in either case. Portions of the tube not representative of the inscription proper are obscured by opaque paint as the section indicated by 9.

In the views the return bends are indicated by 10, 11, 12, 13, 14, 15 and 18. When the bends are formed in this manner it is permissible either to obscure the rearward portion of the bend by means of opaque paint or to leave it clear. According to my invention the reflective surface may be placed on the forward portion and the rearward portion obscured, or the reflective surface may be placed on the rearward portion and the forward portion left clear. I prefer however to use the first method inasmuch as it produces a much more clear cut effect.

It also happens very frequently in the forming of characters that the tube makes a loop and approaches itself to complete the representation of a looped element in the character. It is necessary in all cases that there be some space left at the approaches. Numeral 20 indicates such a condition at the end of the return bend 11. At this point there exists an electric stress equal to the drop in voltage through the looped portion of the tube. The separation, if too great, will spoil the appearance of the sign. If too small, it leads to electric breakdown through the glass.

The third condition is that of cross overs as indicated at 19. Here also the matter of separation is important because of the distortion of the character at an angular view if the separation is too great. It is usual in the best practice to loop one part of the tube back of the other to retain the major portion of the tube in a single plane at such places.

It will also be noticed in connection with the letter "R" that as the tube branches off at 17 at the end of the return bend 11 it is formed to rise to the forward plane of tube contour as indicated by 16. This also conforms to the best practice in tube bending.

There are thus numerous places where a potential exists between adjacent points on the tube. While it might be thought that the importance of such conditions would be determined by the potential drop down the tube between the two points in each case, I have found that other factors are at play making the conditions at such points of the utmost importance. What these factors may be remains a matter of conjecture.

My theory, however, is that high frequency action takes place within the tube between such points. When a conductive coating is placed on the tube this action gives rise to discharges into the air between the adjacent points. It is these free discharges into or through the air which disintegrate the glass at such points resulting finally in breakdown through the glass.

Whether this theory be correct or not is not to be considered as controlling the importance of this disclosure, for it is well known that the effects within gaseous conduction tubes are still subjects of scientific debate.

By following the instructions below it is possible to produce tubes with conductive and reflective coatings which will give as good service as the conventional uncoated tubes. It is to be noted that the precautions given are to be observed even for very short return bends when the actual voltage drop might be thought to be inconsequential.

Referring now to the enlarged view in Figure 4 and the sectional views in Figures 7 and 8 as typical of return bend treatment, we observe that the reflective coating is discontinuous on the tube. The reflective coating is indicated by numerals 30, 31, 32 and 33 being shown in Figure 4 by broken lines. The ends of the various sections of the coating near the junction point 34 are all terminated a short distance back from the junction. This distance is a matter of empirical determination because of the many variables in this work. The opposite ends of the coating 31, 32 and 33 terminate at the ends of the respective arms of the letter "t" and hence do not continue on the under portions of the return bends. The reflective coating is covered by a non-conductive coating of paint or lacquer which is indicated by 34, 35, 36 and 37. This protective coating may well be continued around the tube, covering up the under portions of the return bends as indicated at 38, 39 and 40. In Figure 4 the protective coating is indicated by the full parallel shading lines.

Referring now to Figure 3, I show the preferred manner of coating the tube. The tube is indicated by 41 and the reflective coating by 42. This coating may be formed from any of the metallic substances which have been used for this purpose. I prefer however, the use of aluminum deposited in vacuum. It is preferable to protect the metal by the coating 43 which extends a short distance over the edges of the metal as indicated at 44 and 45. If the protective coating is of light color it assists the reflection at such places. It is usually best to construct this reflector to extend about one half way around the tube.

Again referring to Figure 4; it will be noticed that there are various places where the character outline is not followed by the reflector. Such places are indicated by 46, 47, 48, 49 and 50. By making the protective coating of light color, however, this is partially overcome. I have found, as a matter of fact that, so far as the observer is concerned, such discontinuities become of no consequence. This is due to the fact that the discontinuities fall at the places where the optical effect is enhanced by the approaching tubes. The use of light colored paint thus is sufficient to give an effect continuous to the eye.

With this as typical of the return bend practice, we now refer to Figure 5 and the sectional views in Figures 9 and 10 where I show enlarged

the letter "e". Here the reflective coating is indicated by 51, 52 and 53, being shown in Figure 5 by broken lines. The protective coating is indicated by 54 and in Figure 5 is shown by the 5 full parallel shading lines. We observe that there are two discontinuities in the reflective coating, indicated by 55 and 56. It is permissible in some cases to have a discontinuity at but one place, although the best practice is as shown in the 10 drawings. Here also we have the condition of the optical illusion helping out the effect of a continuous line of light of uniform intensity when light colored protective coating is provided. This may be taken as typical of cross overs.

15 In Figure 6 I show the treatment for approaches as at 20. The vertical stroke of the tube is indicated by 57 and the return bend by 11. Here the reflective coating, indicated by 58 terminates at 59, a short distance back of the 20 junction. The protective coating fills out the character at 60 and completely covers the tube at 61 on the under portion of the return bend. The protective coating on the section 57 is indicated by 10, the reflective coating having been 25 removed from this region.

Referring now to Figure 2, it is to be noted that at the ends of the tube at the points indicated by 62 and 63 terminations of the coating are also to be made. The view is too fine to 30 indicate the coating on the tube, but the position of the ends will be apparent from the above.

The arrangement shown in Figure 3 I have 35 found to be the most satisfactory for the construction of the mirror. It will be noted that the reflective coating is just a little short of semi-circular and that the protective coating passes over the edge a short distance to protect the edges from corona discharges. The protective coating, if of light color assists the reflection at 40 such places as it contacts the glass direct. Dark colored paint, naturally, may be used if desired. However, in cases where a dark obscuring paint is desired, I find it better to apply a light paint first and cover it with dark paint. In installations where the potential is not very high it is not 45 necessary to cover the edges of the coating.

As the most serious cause of breakdown arises 50 at such places as the double backs, the approaches and the cross overs, most careful attention should be given to such places. One should not be misguided here by the fact that the actual potential drop might be very small. For some 55 reason, not yet discovered, the potential drop is not the important factor as compared with the other considerations pointed out above. Coating on parallel sections of tubing should in particular be avoided. At all places where the tubing approaches grounded metal the coating should be eliminated. Such places are found at 60 the electrode terminals.

The most satisfactory material for the reflector 65 is aluminum vaporized and deposited in vacuum. Other materials may be used, however, within the purview of this invention.

In designing signs with tube made according 70 to my method, the designer should bear in mind that the elimination of reflection from the background character in the night is compensated for by the corona glow effect of the tube itself to the eye. This is naturally, an illusion. The effect however is to make the tube appear much wider than it actually is and to make the entire tube appear filled out with the glowing gas. This 75 feature is of considerable importance in the case of tubes of large diameter in which the discharge

tends to pull into the corners and detract from the character. In the case of tubes which develop a "wormy" effect, the reflector also tends to improve the appearance by filling out the tube with light to the eye so that the swirling gas 5 column is not noticed.

The term "character" as used in the claims is to be understood as including any configuration of the tube in representation of letters, numerals, borders, symbols, ornaments or designs or the 10 like.

The term "light colored" is to be understood as including white.

The term "loop" is to be understood as defining any configuration of the tube in which it 15 follows a course from a given point through a portion of a character and returns to or near the said point.

Having thus described my invention, what I 20 claim is:

1. A luminous tube in the form of a character having a portion which crosses over itself, a reflective coating of metallic nature on said tube on the outside surface thereof and on the side 25 distant from the normal position of the observer, said coating being formed with a discontinuity on at least one of the portions of said tube at the crossing point whereby to increase the air space distance between the approaching portions of said coating, and a reflective coating 30 of non-conductive nature on said tube extending across the said discontinuity to provide a continuous reflective coating on said tube corresponding to said character.

2. A luminous tube in the form of a character 35 having at least one portion formed to represent a branching character stroke, a reflective coating of metallic nature on said tube on the side thereof opposite the normal direction of the observer, said coating being terminated a distance from 40 the junction thus formed on at least one of its arms at said junction, said distance being sufficiently large to substantially prevent deleterious discharges at said junction and a coating of light colored non-conductive material covering 45 the discontinuity in the reflective surface thus provided.

3. A luminous tube in the form of a character, said tube forming a loop over a part of the course thus traced and returning toward itself 50 without actually touching, a reflective coating of metallic nature on said tube on the side thereof opposite the normal direction of the observer, said coating terminating a short distance from the junction thus represented on at least one 55 branch of said tube thereat, said distance being sufficiently large to substantially prevent deleterious discharges at said junction, and a coating of light colored non-conductive material completing the reflector thus provided across the 60 discontinuity thus formed.

4. A luminous tube in the form of a character and having a section returning over its own course to a branching junction of said character and a reflective coating of conductive material disposed 65 lengthwise along an outside surface of said tube, said tube being characterized by virtue of the presence of said coating by a tendency to electric breakdown at said section materially in excess of the breakdown tendency due to the proportionate voltage drop along said section with respect to the voltage impressed across the extreme 70 terminals of said tube, said coating being confined to one of the opposing branches of said tube in said section to substantially prevent break- 75

down thereat because of said excessive breakdown tendency.

5. A luminous tube in the form of a character and having a section returning over its own course to a branching junction of said character and a reflective coating of conductive material disposed lengthwise along an outside surface of said tube, said tube being characterized by virtue of the presence of said coating by a tendency to 10 electric breakdown at said section materially in excess of the breakdown tendency due to the proportionate voltage drop along said section with respect to the voltage impressed across the extreme terminals of said tube, said coating being confined to one of the opposing branches of said tube in said section and terminating a sufficient distance back from said junction on at least one of the branches of said tube from said junction to substantially compensate for said excessive breakdown tendency.

6. A luminous tube in the form of a character having a section in the form of a loop of said character with spaced portions of said tube crossing each other at the junction of said loop and a reflective coating of conductive material disposed lengthwise along an outside surface of said tube, said tube being characterized by virtue of the presence of said coating by a tendency to electric breakdown at such approaching portions 25 when continuously coated therealong materially in excess of the breakdown tendency due to the proportionate voltage drop along said section with respect to the voltage impressed across the extreme terminals of said tube, said coating terminating on at least one of said portions at said junction a sufficient distance from the other said portion of said tube at said junction to compensate for said excessive breakdown tendency.

7. A luminous tube in the form of a character 40 having a section in the form of a loop of said character with spaced portions of said tube closely approaching each other at the junction of said loop and a reflective coating of conductive material disposed lengthwise along an outside

surface of said tube, said tube being characterized by virtue of the presence of said coating by a tendency to electric breakdown at such junction if continuously coated thereat materially in excess of the breakdown tendency due to the proportionate voltage drop along said section with respect to the voltage impressed across the extreme terminals of said tube and a breakdown tendency materially less than said excessive breakdown tendency if said coating be confined to one 10 of said portions of said tube at said junction, said coating terminating on one of said portions at said junction a sufficient distance from the other portion of said tube at said junction to limit the breakdown tendency to a value materially less 15 than said excessive value.

8. A luminous tube provided with a reflective coating of conductive material disposed lengthwise along an outside surface thereof and having a configuration in its outline, said tube being 20 characterized by a materially greater tendency to electric breakdown at said configuration if said coating is continuous thereat than if some of said coating is removed from the surface of said tube thereat, said excessive breakdown tendency being materially greater than the proportionate breakdown tendency with respect to the voltage impressed across the extreme terminals of said tube, said tube being selectively coated at said configuration to reduce said breakdown tendency 25 thereaccording.

9. A luminous tube provided with a reflective coating of conductive material disposed lengthwise along an outside surface thereof and having a configuration in its outline, said tube being 30 characterized by a tendency to electric breakdown at said configuration greatly in excess of the proportionate voltage drop thereat with respect to the voltage impressed across the terminals of said tube in normal operation thereof, and 35 means to prevent electric breakdown at said configuration.

ARTHUR CLIFTON DEANS.
